UNITED STATES PATENT OFFICE.

FREDERICK A. BOLLINGER, OF AKRON, OHIO, ASSIGNOR TO THE OLDFIELD TIRE COMPANY, OF CLEVELAND, OHIO, A CORPORATION OF OHIO.

DESIGN FOR A PNEUMATIC TIRE.

58,541.

Specification for Design.

Patented Aug. 2, 1921.

Application filed March 14, 1921. Serial No. 452,322. Term of patent 14 years.

To all whom it may concern:

Be it known that I, FREDERICK A. BOLLINGER, a citizen of the United States, residing at Akron, in the county of Summit and State of Ohio, have invented a new, original, and ornamental Design for Pneumatic Tires, of which the following is a specification, reference being had to the accompanying drawing, forming a part thereof.

In the drawings Figure 1 is side elevation.

Fig. 2 is a top plan view.

Fig. 3 is a section on line 3—3 of Fig. 2.

Fig. 4 is a developed plan view of the tire tread.

I claim:

The ornamental design for a pneumatic tire as shown.

FREDERICK A. BOLLINGER.
